(57) **CLAIM**

The ornamental design for a pad kit for a helmet, as shown and described.

DESCRIPTION

FIG. 1 is a perspective view of a pad kit for a helmet showing my new design;

FIG. 2 is a front elevational view thereof;

FIG. 3 is a rear elevational view thereof;

FIG. 4 is a side elevational view thereof;

FIG. 5 is a side elevational view of a side opposite that shown in FIG. 4;

FIG. 6 is a top plan view thereof;

FIG. 7 is a bottom plan view thereof;

FIG. 8 is a perspective view of a pad kit for a helmet showing my new design;

FIG. 9 is a front elevational view of the pad of FIG. 8;

FIG. 10 is a rear elevational view of the pad of FIG. 8;

FIG. 11 is a side elevational view of the pad of FIG. 8;

FIG. 12 is a side elevational view of a side opposite that shown in FIG. 11;

FIG. 13 is a top plan view of the pad of FIG. 8;

FIG. 14 is a bottom plan view of the pad of FIG. 8;

FIG. 15 is a perspective view of another pad kit for a helmet showing my new design;

FIG. 16 is a front elevational view of the pad of FIG. 15;

FIG. 17 is a rear elevational view of the pad of FIG. 15;

FIG. 18 is a side elevational view of the pad of FIG. 15;

FIG. 19 is a side elevational view of a side opposite that shown in FIG. 18;

FIG. 20 is a top plan view of the pad of FIG. 15;

FIG. 21 is a bottom plan view of the pad of FIG. 15;

FIG. 22 is a perspective view of another pad kit for a helmet showing my new design;

FIG. 23 is a front elevational view of the pad of FIG. 22;

FIG. 24 is a rear elevational view of the pad of FIG. 22;

FIG. 25 is a side elevational view of the pad of FIG. 22;

FIG. 26 is a side elevational view of a side opposite that shown in FIG. 25;

FIG. 27 is a top plan view of the pad of FIG. 22; and,

FIG. 28 is a bottom plan view of the pad of FIG. 22.

The individual pads are shown separately for clarity.

The broken lines in the drawings are for the purpose of illustrating environment only and form no part of the claimed design.
